CLAIM

The ornamental design for a terminal device, as shown and described.

DESCRIPTION

FIG. 1 is a front perspective view of a terminal device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines represent portions of the terminal device and form no part of the claim. The oblique line shading shown in FIGS. 1 and 2 represents a tinted glass surface.
